DESIGN FOR A DENTAL FLOSS RECEPTACLE

Homer H. Bashore, Bucyrus, Ohio

Application February 13, 1948, Serial No. 144,466

Term of patent 7 years

(Cl. D24—1)

To all whom it may concern:

Be it known that I, Homer H. Bashore, a citizen of the United States, residing at Bucyrus, in the county of Crawford and State of Ohio, have invented a new, original, and ornamental Design for a Dental Floss Receptacle, of which the following is a specification, reference being had to the accompanying drawing, forming a part thereof.

Fig. 1 is a substantially enlarged side elevational view of a dental floss receptacle showing my new design.

Fig. 2 is a top view thereof.

I claim:

The ornamental design for a dental floss receptacle, as shown.

HOMER H. BASHORE.
